UNITED STATES PATENT OFFICE.

WILLIAM G. ZEPF, OF TROY, NEW YORK, ASSIGNOR TO WHITEHURST PRINTING AND BINDING COMPANY, OF TROY, NEW YORK, A CORPORATION OF NEW YORK.

GUMMING MACHINE.

Application filed March 5, 1927. Serial No. 173,013.

Reference may be had to the accompanying drawings, and the reference characters marked thereon, which form a part of this specification. Similar characters refer to 5 similar parts in the several figures therein.

The principal object of the invention is to facilitate the application to sheets of paper or the like of an adhesive substance covering more or less of the area of the sheet.

10 The invention relates more particularly to means designed to facilitate the delivery from the machine and handling of the sheet before the adhesive coating has become dry.

Other objects will appear in connection 15 with the following description.

Fig. 1 of the drawings is a top plan view of a gumming machine embodying my invention.

Fig. 2 is a view in front elevation of the 20 same.

Fig. 3 is a section in elevation of the left-hand end of the machine, as viewed in Figs. 1 and 2, partly broken away.

Fig. 4 is a vertical section of a machine 25 taken from front to rear on the broken line 4-4 in Fig. 1.

Fig. 5 is a vertical section taken on the broken line 5-5 in Fig. 4, longitudinally of the conveyer which delivers the gummed 30 sheets from the machine.

Fig. 6 is a view in perspective of one of the sickle-shaped strippers removed from the machine.

Fig. 7 is a view in perspective of one of 35 the side guides removed from the machine.

Fig. 8 is a view in perspective of one of the removable trays loaded with gummed sheets.

Fig. 9 is a view in perspective of a removable tray of modified form.

Referring to the drawings wherein the invention is shown in preferred form, 1 is the frame of the machine having a bed or feed table, 2, leading from the front of the 45 machine to a point adjacent to a gumming roll, 3, carried by a shaft, 4, rotatively mounted in bearings on the frame of the machine.

The lower portion of the gumming roll, 3, 50 is adapted to run immersed in a liquid adhesive, 5, which may be glue, mucilage or

the like contained in a tank, 6, mounted upon the frame of the machine, as shown in Fig. 4.

An endless belt, 7, is carried by rollers, 8 and 9, with its lower stretch in close proximity to the bed or table, 2, which belt is driven in a direction to cause its said lower stretch to feed the blanks over the surface of the bed or table, 2, toward the gumming roll, 3.

One or more sheet-supporting rolls, 10, are also mounted on the shaft, 4, at different distances from the gumming roll, 3, to support the portion of the sheet which is outside the area of the zone to which the adhesive is to be applied by the gumming roll, 3.

In rear of the roll, 8, is a roll, 12, in close proximity to the path of the sheet of paper as it passes over the gumming roll, 3.

Above the roll, 12, is another roll, 13, connected with the roll, 12, by driving belts, 11.

The belt, 7 and the roll, 12, preferably do not engage the gumming roll, but tend to direct the sheet through a curved path such that the desired portion of the sheet shall be caused to engage and take the gum or adhesive from the gumming roll, 3.

A plurality of belts, 7, may be employed if desired to insure the proper feeding of 80 the sheets.

For certain purposes of the invention, the sheets may be fed to and past the gumming roll, 3, by hand or in any other known manner.

85 Mounted upon the frame of the machine above the gumming roll, 3, is a sickle-shaped stripper, 14, which has its lower end, 15, projected downwardly and forwardly across the path of a sheet fed through the machine 90 and adapted to intercept the gummed sheet and strip the same from the gumming roll, 3.

In advance of the gumming roll, 3, I provide a conveyer, 17, preferably in the form of an endless belt, the upper stretch of 95 which is movable above and transversely of the path of the sheet as the sheet is fed to the gumming roll, and the lower or return stretch of which extends beneath the bed or table, 2.

100 The stripper, 14, is upwardly and retroversely curved to overhang the path of the

sheet in advance of the gumming roll, and preferably also to overhang the upper stretch of the conveyer, 17, as shown in Figs. 3 and 4.

5 The stripper, 14, thus serves to intercept the gummed sheet, guide the same through a retrovert path, and introvert the sheet to deliver it upsidedown,—that is, with its gummed surface uppermost, in a position in 10 advance of the gumming roll.

The sheet is thus deposited with more or less of its length superimposed upon the upper stretch of the conveyer, 17, or upon a tray, 18, removably carried by said conveyer.

15 When the construction of the machine makes it practicable, the conveyer, 17, is extended laterally approximately to the gumming roll, 3.

In the type of machine shown in the drawings the inner edge of the belt terminates at some distance from the gumming roll, and a shelf, 19, is mounted upon the frame of the machine in position to form a slideway to support the ends of the sheets which extend beyond said side of the belt, whereby said ends of the sheet are supported, but permitted free sliding movement as the sheets are carried by the conveyer to one side of the path of the sheet to the gumming mechanism.

30 As the rear end of the introverted sheet falls upon the roll, 13, said roll serves to help feed the introverted sheet upon the conveyer, 17, or tray, 18.

35 A plurality of trays, 18, may be employed and placed successively on the upper stretch of the conveyer, 17, the speed of which is such that a plurality of gummed sheets will be deposited upon each tray during the time 40 required for its movement transversely of the path of feed of the sheets to the gumming mechanism.

The sheets will thus be deposited upon the tray in lapping position with their gummed 45 areas uncovered as shown in Fig. 8, and as a tray passes beyond the path of said movement of the sheets to the gumming mechanism, the loaded tray can be removed from the conveyer, and placed in a convenient location for permitting the gummed sheets to dry.

I have shown two strippers, 14, but as many strippers may be employed as are found necessary for the proper inversion 55 and delivery of sheets of the width under treatment.

On opposite sides of the path into which the stripped sheets are directed by the stripper, 14, I mount side guides, 20, to prevent 60 lateral displacement of the sheets.

The several strippers, 14, are mounted upon the frame of the machine by means of a yoke, 21, provided with slots, 22, slidably engageable with a cross-bar, 23, fixed upon 65 the frame of the machine.

The several guides, 20, are carried by a bracket, 24, also slidably mounted upon the cross-bar, 23.

The strippers, 14, and guides, 20, can thus be adjusted to adapt them for the treatment 70 of sheets of different widths.

The tray, 18, may if desired, be formed with an upright edge flange, 18^a, to assist in guiding and supporting along one edge, the sheets deposited thereupon.

75 The trays, 18, may be made of a width to extend more or less beyond the inner side edge of the conveyer, 17, and if desired, they may be so far extended as to make use of the shelf, 19, unnecessary.

80 The end, 16, of the stripper may be made of flexible material, permitting it to be readily bent by hand to different forms to better adapt it for operation upon sheets of different material and differing in thickness, 85 and flexibility, as indicated in Fig. 4.

The shaft, 4, has fixed thereon a gear, 25, in engagement with a pinion, 26, on a shaft, 27, driven by a pulley, 28, connected by a belt, 29, with the shaft, 30, of an electric 90 motor, 31.

The endless carrier, 17, is mounted upon an idle roll, 32, and a roll, 33, fixed upon a shaft, 34, upon which shaft is also fixed a belt pulley, 35, connected by belt, 36, with 95 a smaller pulley, 37, fixed upon a shaft, 38, which shaft, 38, has fixed thereupon a pulley, 39, connected by a belt, 40, with a smaller pulley, 41, fixed upon a shaft, 42.

A pulley, 43, fixed upon the shaft, 42, is 100 connected by a cross-belt, 44, with a pulley, 45, fixed upon the electric motor shaft, 30.

Guides or gages, 46, may be mounted upon the frame of the machine above the upper stretch of the conveyer, 17, adapted to engage 105 the outer edges of the tray, 18, and the gummed sheets deposited thereon.

The strippers, 14, are preferably placed opposite at intervals between the rolls, 3 and 10.

110 The operation of the machine is as follows:

A sheet, 47, is placed by hand upon the bed or table, 2, and pushed below the lower stretch of the belt or belts, 7, whereby the sheet is moved toward and against the gumming roll, 3, and supporting rolls, 10.

115 The sheet is thus brought into engagement with the belt or belts, 11, which assists in further feeding the sheet against the surface of the gumming roll until the inner end of the sheet is brought into engagement with the upwardly and retroversely curved stripper, 14, as said end of the sheet is stripped from the rolls, 3 and 10, by the 120 forwardly projecting forward end, 15, of the stripper which extends below the path of the sheet in an interval between certain of the rolls, 3 and 10.

125 As the feed movement of the sheet is con- 130

tinued by cooperation of the belts, 7 and 11, with the rolls, 3 and 10, the stripper, 14, serves to guide the sheet retroversely toward the front of the machine, thereby introverting the sheet so that its gummed surface is uppermost.

The introverted sheet falls more or less upon the belt, 7, or a tray, 18, carried by the belt, and it may fall partly upon the 10 belts, 11, which help to feed the sheet well upon the conveyer belt or tray.

The movement of the conveyer belt or tray is quite slow as compared with the general feed movement of the sheet, so that the conveyer and its tray, 18, during the interval while each sheet is being gummed, introverted and deposited thereupon, moves a distance only slightly greater than the width of the zone to which the adhesive is applied.

20 The sheets are thus deposited upon the tray, 18,lapping one another, but with their gummed edges uncovered as shown in Fig. 8.

As a loaded tray is carried transversely out of the path of the gummed sheets, it is 25 removed from the conveyer belt and placed in a convenient place to permit the adhesive to dry.

In Figs. 1 and 5, I have shown the machine provided with a second gumming roll, 3^a, whereby either side edge of the sheet may 30 be gummed as desired.

What I claim as new and desire to secure by Letters Patent is

1. In a gumming machine and in combination, a gumming roll in the path of a sheet fed through the machine; a conveyer movable above and transversely of the path of the sheet in advance of the gumming roll; and a stripper in the path of the gummed sheet 35 40 and retroverted to overhang the path of the sheet in advance of the gumming roll above the plane of the conveyer.

2. In a gumming machine and in combination, a gumming roll in the path of a sheet fed through the machine; a conveyer movable above, and transversely of, the path of the sheet in advance of the gumming roll; and a stripper in the path of the gummed sheet 45 50 and retroverted to overhang the conveyer.

3. In a gumming machine and in combination, a gumming roll in the path of a sheet fed through the machine; an endless conveyer extending above, below and transversely of, the path of the sheet in advance 55 60 of the gumming roll; and a stripper in the path of the gummed sheet and retroverted to overhang the upper stretch of the conveyer.

4. In a gumming machine and in combination, a gumming roll in the path of a portion of a sheet fed through the machine; a sheet-supporting roll in the path of another portion of said sheet; a conveyer movable above, and transversely of, the path of the sheet

in advance of said rolls; and a stripper in 65 the path of the gummed sheet, one end of the stripper extending between said rolls and its other end being retroverted to overhang said conveyer.

5. In a gumming machine and in combination, a gumming roll in the path of a sheet fed through the machine; a conveyer movable above and transversely of the path of the strip in advance of the gumming roll; and a sickle-shaped stripper in the path of 75 the gummed sheet with its upper end retroverted to overhang the conveyer.

6. In a gumming machine and in combination, a gumming roller in the path of a sheet fed through the machine; a conveyer movable above and transversely of the path of the sheet in advance of the gumming roll; a stripper in the path of the gummed sheet and retroverted to overhang the path of the sheet in advance of the gumming roll above 80 85 the plane of the conveyer; and a rearwardly feeding roll beneath the overhanging portion of the stripper between the stripping end of the stripper and the conveyer.

7. In a gumming machine and in combination, a gumming roller in the path of a sheet fed through the machine; a conveyer movable above and transversely of the path of the sheet in advance of the gumming roll; a stripper in the path of the gummed sheet 90 95 and retroverted to overhang the path of the sheet in advance of the gumming roll above the plane of the conveyer; and a removable tray carried by the conveyer.

8. In a gumming machine and in combination, a gumming roller in the path of a sheet fed through the machine; a conveyer movable above and transversely of the path of the sheet in advance of the gumming roll; a stripper in the path of the gummed sheet 100 105 and retroverted to overhang the path of the sheet in advance of the gumming roll above the plane of the conveyer; and a removable tray carried by the conveyer and projecting therefrom toward the gumming roll.

9. In a gumming machine and in combination, a gumming roll in the path of a sheet fed through the machine; a bed over which the sheet is fed to the gumming roll; a feed belt above said bed and cooperative therewith to feed the sheet to the gumming roll; a feed-roll cooperative with the gumming roll in rear of said first mentioned feed belt; a conveyer movable above and transversely of said first mentioned feed belt; and a stripper in the path of the gummed sheet in rear of said belts, and retroverted to overhang the path of the sheet in advance of the gumming roll above the plane of the conveyer.

In testimony whereof, I have hereunto set my hand this 1st day of March, 1927.

WILLIAM G. ZEPF.
